(57) CLAIM

The ornamental design for a motor vehicle and toy replica thereof, as shown and described.

DESCRIPTION

FIG. 1 is a front perspective view of a motor vehicle and toy replica thereof of our new design;

FIG. 2 is a rear perspective view thereof;

FIG. 3 is a right side view thereof, the left side view being a mirror image thereof, except for the fuel door, which is not present on the left side, and the front wipers which are not symmetrical;

FIG. 4 is a front view thereof;

FIG. 5 is a rear view thereof;

FIG. 6 is a top plan view thereof;

FIG. 7 is a front perspective view of a second embodiment of a motor vehicle and toy replica thereof of our new design;

FIG. 8 is a rear perspective view thereof;

FIG. 9 is a right side view thereof, the left side view being a mirror image thereof, except for the fuel door, which is not present on the left side, and the front wipers which are not symmetrical;

FIG. 10 is a front view thereof;

FIG. 11 is a rear view thereof; and,

FIG. 12 is a top plan view thereof.

The bottom view of our design and the interior of the automobile as depicted in FIG. 12 form no part of the claimed design.
